UNITED STATES PATENT OFFICE.

JOSEPH A. QUERY, OF SOMERVILLE, MASSACHUSETTS.

BONBON-MAKING MACHINE.

Application filed April 24, 1924. Serial No. 708,736.

In my application for a United States patent, Serial No. 590,193, I have shown a machine for depositing individual nut meats in moulds to be afterward covered with chocolate coatings or otherwise as desired. This machine has worked exceedingly well with nut meats. My present invention relates to a similar machine adapted more particularly for use with cherries and other small fruits which being in themselves more delicate, require a somewhat more careful handling.

My invention will be understood by reference to the drawings, in which—

Figure 1 is a plan of a machine embodying my invention.

Fig. 2 is a section on line 2—2; of Fig. 1.

Figs. 3 and 4 being similar sections with the parts located, however, in different positions, and

Fig. 5 is an end elevation.

1 is a stationary table mounted on legs 2, 2 braced by suitable cross pieces 3, 3. This table is perforated as at 4, 4 with openings 23 of such location, size and shape as may be desired in view of the article to be deposited, as is shown at 5, 5 (see Fig. 2). This table is of considerable size, but its size and shape may be varied as desired. It 30 has upwardly-projecting side walls 41 and inwardly-projecting portions 42 to form grooves 43 in which may slide the upper slide plate 6. This upper slide plate 6 is perforated as at 8 and has side and end walls 7, this plate forming in a sense a hopper in which the fruits or nuts are deposited more or less in bulk. The side walls 7 are located a short distance from its side edges to form guide pieces 61 which slide 40 in the grooves 43. Its perforations 8 are the size of the perforations 4 in the table 1 and are arranged so that upon sliding the upper plate 6 into the position shown in Fig. 3 these perforations 8 will register with the perforations 4 in the table, and means 45 are provided, as will be described below, whereby a proper limited movement may be given to this upper slide plate for this purpose.

Below the table 1 is mounted a lower plate 9 which also is provided with perforations 10 similar in size, shape and location to the perforations 4 and 8 in the table and upper slide plate, respectively. The table and both 55 slide plates are slotted as at 11 and through

the slots are passed bolts 12 with suitable nuts, this arrangement being such that the lower plate is held against the bottom of the table, and both the upper and lower plates may be given a slight longitudinal movement to bring their respective openings 8 and 10 at suitable times in register with the openings 4 in the table 1.

To move these slide plates I provide levers 13 and 14. These levers 13 and 14 are 65 mounted in a bracket 15 which bracket is supported on the upturned end 16 of the table 1, being secured thereto by bolts. The lever 13 is attached by the pivoted link 19 to the top slide 6 so that by moving the free 70 end of the lever 13 the top slide will be moved. In like manner the lower slide 9 is connected by the pivoted link 191 to the lever 14 so that it may be moved in or out as occasion may require.

These parts being in the position shown in Fig. 2, the top slide hopper 7 is filled with the articles to be deposited and they fall by gravity so far as may be into the openings 8 in the floor 6 of the hopper. The 80 operator standing at the left hand end of the apparatus (see Fig. 1) pulls the lever 13 towards him. This causes the perforations 8 in the floor 6 of the hopper 7 to register with the openings 4 in the table 1 85 as shown in Fig. 3, thus segregating the various nut meats, cherries, or whatever the articles may be, from each other in their respective openings 4 in the table 1, after which the lever 13 is returned to its original position, thus preventing the meats, etc. from piling up in the openings in the table, and at the same time filling the perforations 8 with another charge of nuts, etc.

Thereafter the operator pushes in the lever 14, thus causing the registration of the openings 10 in the lower slide with the openings 4 in the table 1 and allowing the contents of these openings to drop through onto the receiver below.

The preferred form of receiver is one like that shown in section in Figs. 2, 3 and 4 of the drawings and comprises a mould box 20 which may be of any desired construction carrying the usual starch mould 241 105 with starch pockets or cavities 24. This mould box is set on slideways 21 mounted on legs 22 and their braces 221 and properly centered by means of brackets 23 and guide plates 25 so that each cavity 24 may be lo- 110

cated under one of the openings 4 in the table 1 when the mould box is properly placed. Thus when the lower slide 9 has been moved to release the contents of the perforations 4 such contents will fall into the cavities 24 in the mould and will thereafter be treated in any desired way. The slideways 21 are of any desired length, preferably long enough to support a number of these mould boxes so that when one mould box is filled it may be pushed out of the way in the act of pushing an empty mould box into place.

The simplicity of construction of my machine will be apparent. While the means of connecting the links 19 and 191 with the upper slide 6 may be of any desired construction, I have shown such connection to be a bolt 26 which passes down through one wall of the hopper 7 and through a proper opening in the links 19 and 191, thus pivoting the links properly so that the lever may be operated without jamming.

Other means of embodying my invention will occur to those skilled in the art, the details of my machine being variable according to circumstances.

What I claim as my invention is:—

1. In a machine of the kind described, a stationary perforated member and two slide members, each having perforations located and adapted to be brought into register with the perforations in said stationary member, said slide members being located one above and the other below said stationary member, said upper slide member having upstanding walls so as to be adapted to serve as a hopper to receive and distribute ma-

terial into said perforations in said stationary member.

2. In a machine of the kind described, a stationary perforated table, a slide thereon having upstanding walls so as to be adapted to serve as a hopper, said slide having perforations and being adapted to be moved whereby it may bring its perforations into register with the perforations of said table, and a second perforated slide located under said table and adapted to open and close the perforations in said table.

3. In a machine of the kind described, a stationary perforated member and two slide members each having perforations located and adapted to be brought into register with the perforations in said stationary member, said slide members being located one above and one below said stationary member, said upper slide member having upstanding walls so as to be adapted to serve as a hopper; whereby when the perforations of said upper slide member are in register with the perforations in said stationary member material in the perforations of said upper member will be fed to the perforations in said stationary member and may be held therein by said lower slide member, in combination with a mold located below said lower slide member and having cavities registering with the perforations in said stationary member whereby when the perforations of said lower slide member are brought into register with the perforations in said stationary member the contents of said stationary member will be discharged into the cavities in said mold.

JOSEPH A. QUERY.
